UNITED STATES PATENT OFFICE.

SAMUEL G. RIGDON, OF INDIANAPOLIS, INDIANA, ASSIGNOR TO GEORGE F. KREITLEIN,
OF INDIANAPOLIS, INDIANA.

DESIGN FOR A VEHICLE-TIRE TREAD.

51,512.

Specification for Design.

Patented Nov. 20, 1917.

Application filed September 25, 1916. Serial No. 122,174. Term of patent 3½ years.

To all whom it may concern:

Be it known that I, SAMUEL G. RIGDON, a citizen of the United States, residing at Indianapolis, in the county of Marion and State of Indiana, have invented a new, original, and ornamental Design for Vehicle-Tire Treads, of which the following is a specification, reference being had to the accompanying drawing, forming a part thereof.

Figure 1 is a transverse section of a tire embodying my design and Fig. 2 is a developed plan of a fragment of the tread of said tire.

My design comprises a central rib on each side of which are a plurality of series of connected studs or bosses extending circumferentially around the face or tread of the tire, each of said series comprising substantially

circular bosses and elongated bosses alternately arranged, said bosses being slightly larger at their bases than at their tips and adjacent bosses being connected by a short rib arranged substantially in the medial line of the series and of less height than the height of the bosses. The several circumferential series of bosses are arranged so that the circular bosses of one series will be laterally adjacent the elongated bosses of adjacent series.

I claim:

The ornamental design for a vehicle tire tread as shown and described.

In witness whereof, I have hereunto set my hand at Indianapolis, Indiana, this 23rd day of September, A. D. one thousand nine hundred and sixteen.

SAMUEL G. RIGDON.
